UNITED STATES PATENT OFFICE.

JOHN R. NESTER, OF BOYERTOWN, PENNSYLVANIA.

CASKET TOP AND PANEL FASTENER.

Application filed June 18, 1923. Serial No. 646,169.

To all whom it may concern:

Be it known that I, JOHN R. NESTER, a citizen of the United States, residing at Boyertown, in the county of Berks and State of Pennsylvania, have invented new and useful Improvements in Casket Top and Panel Fasteners, of which the following is a specification.

This invention relates to locks for casket tops and panels, and is to a large extent an improvement on my co-pending application, Serial No. 528,936. The object of the present invention is to provide a structure of greater simplicity, which may be more accurately and quickly secured to a burial casket, and which is therefore more positive in its action.

Another object is to provide a structure in which the parts are assembled by securing them to the casket, thereby avoiding an assembling operation prior to the operation of securing the lock in place.

With these and other objects in view, the invention resides in certain novel features of construction and combination and arrangements of parts, the essential features of which are hereinafter fully described, are particularly pointed out in the appended claims, and are illustrated in the accompanying drawing, in which:—

Figure 1 is a side elevation of the locking means, with fragmentary portions of the burial casket in section.

Figure 2 is a detached perspective view of the members comprising the locking means or complete device.

Figure 3 is a longitudinal sectional view of the lowermost member.

Like characters of reference refer to like parts in all the views.

Referring to the drawing in detail, 10 represents a portion of a casket, which is morticed out at 11 to receive the principal portion of the locking device. This portion 45 of the locking device consists essentially of three parts,—a lower plate 12, an upper plate 13, and an interposed latch 14.

The lower plate 12, is formed with a central aperture 15, for permitting the passage 50 of the tongue of the hasp member later to be described. At one end, the plate 12, is formed with a screw hole 16 and at the other with an apertured boss 17, which is punched up from the plate to a height equal 55 to the thickness of the latch member 14.

The upper plate 13 is formed with an

elongated central slot 18 which registers with the slot 15, and with screw holes 19 which register respectively with the hole 16 and the hole in the boss 17. 60

The latch member 14 is formed with a locking nose 20 for insertion into the eye of the hasp member and with a finger piece 21 for operation of the latch. It is provided with a screw hole in the end opposite the finger piece and through this one of the retaining screws passes thereby forming the pivot of the latch member. It will also be seen that the back of the latch member is flat as at 22 and this flat part co-operates 70 with the end of the mortice 11 to form a limit for the outward movement of the latch.

The hasp member is the same as in my co-pending application above referred to, and as shown consists of a body 23 provided 75 with screw holes for effecting the securing of the device to the casket. From the body 23 there depends a tongue 24 in which there is formed a locking eye 25.

The lock is adapted for securing the entire top on a casket or for securing panels in place thereon as may seem most desirable. In operation, the tongue 24 is thrust through the slots 18 and 15 in the plates 13 and 12 and this brings the eye 25 in registry with the aperture between these plates. The latch member 14 is then moved to bring its nose 20 into the eye 25. The distance between the plates is positively determined by the latch 14 and the boss 17. The degree 90 of frictional tension on the locking latch 14 may be determined by adjustment of the securing means.

While I have described what I deem to be the most desirable embodiment of my invention, it is obvious that many of the parts may be varied without in any way departing from the spirit of my invention, and I therefore do not limit myself to the exact details of construction herein shown 100 nor to anything less than the whole of my invention limited only by the appended claims.

What I claim is:—

1. In a device of the class described, the combination of a bottom plate formed with a boss, an upper plate, and a locking latch pivoted therebetween at the end of the plates opposite the said boss. 105
2. In a device of the class described, the combination with a pivoted locking latch of a lower plate formed with a boss the thick- 110

ness of said latch, an upper plate, and a securing member passing through the first three members to secure them to a casket and to form the pivot of said locking latch.

5. A casket lock comprising an apertured hasp, an apertured bottom plate and an upper apertured plate for receiving said hasp, a boss on said bottom plate, a locking latch pivoted between the bottom and upper plates at the end of the plate opposite to said boss, and a locking nose on said latch for insertion through said hasp.

10 6. A casket lock comprising a bottom plate, a pivoted locking latch, an upper plate, a boss formed on said bottom plate the thickness of said latch, a securing member passing through the latch, upper and bottom plates to secure them to a casket and to form a pivot for said locking latch,

20 said bottom and upper plates being apertured, and a hasp for insertion through said apertures and co-operation with said locking latch.

5. A casket lock comprising a bottom plate, a pivoted locking latch, an upper 25 plate, a securing member passing through the latch, upper and bottom plates to secure them to a casket and to form a pivot for said locking latch, said bottom and upper plates being apertured, a hasp for insertion 30 through said apertures and co-operation with said locking latch, said hasp being perforated, and a locking nose on the latch adapted for insertion through the perforations in the hasp.

35 In testimony whereof I affix my signature.

JOHN R. NESTER.
